UNITED STATES PATENT OFFICE.

GEORGE DOUGHERTY, OF TIFFIN, OHIO, ASSIGNOR TO UNITED STATES GLASS COMPANY,
OF PITTSBURGH, PENNSYLVANIA, A CORPORATION OF PENNSYLVANIA.

DESIGN FOR A GLASS VESSEL.

48,515.

Specification for Design.

Patented Feb. 8, 1916.

Application filed November 9, 1915. Serial No. 60,603. Term of patent 7 years.

To all whom it may concern:

Be it known that I, GEORGE DOUGHERTY, a citizen of the United States, and residing at Tiffin, in the county of Seneca and State of Ohio, have invented a certain new, original, and ornamental Design for a Glass Vessel, of which the following is a specification, reference being had to the drawing forming a part thereof, in which the vessel is illustrated in side elevation.

I claim:—

The ornamental design for a glass vessel, substantially as shown.

GEORGE DOUGHERTY.

Witnesses:

CHAS. R. BOUR,
A. G. DAMP.
